United States Patent Office

Des. 198,359
Patented June 9, 1964

198,359

MOUTH GUARD

Wallace John McLeod, 1182 Tecumseh Park Drive, Port Credit, Ontario, Canada, assignor of one-half to A. Gordon Owen, Islington, Ontario, Canada

Filed Nov. 4, 1963, Ser. No. 77,258

Term of patent 7 years

(Cl. D3—13)

I claim:

The original design for a mouth guard, as shown and described.
